CONTAINERS FOR ELECTRICAL BULBS AND THE LIKE

Kermit Greene, Newton Center, Mass., assignor to St. Regis Paper Company, New York, N.Y., a corporation of New York

Filed Apr. 8, 1963, Ser. No. 271,311
4 Claims. (Cl. 206—46)

This invention relates to containers and blanks for forming same, for use in the packaging of electric lamp bulbs and other electric bulbs and the like frangible objects.

The packaging of such objects in a manner which will be highly economical while insuring adequate protection thereof and still leaving same readily accessible for customer inspection or removal, has involved problems which have not heretofore met with an ideal solution. Such bulbs are often simply placed in open-ended elongated containers of square cross-section and formed of single-faced corrugated paperboard. The ends of such containers have been covered by wrapping the package in a covering sheet or the like with portions of such sheet at the end folded thereover. Such packages, however, after some handling, may allow the contained objects to slip out and become broken, particularly if whatever wrapping is used to provide the end closures therefor, is not securely positioned. For convenience of manufacture and shipment, it is desirable to make such packages of square cross-section even though the bulbs contained therein are of circular cross-section. This may result, after handling of the packages, in causing the container to become of more or less rounded cross-section, thus allowing the contained bulbs more readily to slip out. While many different forms of paperboard insert partitions and the like have been proposed for such packages for more securely retaining in position the objects therein, these have involved considerable expense considering the highly competitive conditions and further involve inconveniences in packing, and ready removal of the objects therefrom, or in opening same for customer inspection.

The present invention provides a form of container and container blank for the above-indicated purposes, and which will involve substantially no further expense either in the manufacture of the blanks or in inserting the objects therein, than is involved in the plain containers of square cross-section such as above referred to and yet the construction is such as securely to retain the bulbs or other frangible objects against sliding out of place and at the same time strengthening the container against any such deflections of the walls thereof as might tend to allow the contained objects to slip out.

In accordance with the invention, a die-cut blank is provided of paperboard, preferably although not necessarily, corrugated paperboard, for example single-faced corrugated paperboard, creased to provide a succession of hinged-connection wall portions, for example four walls in the usual case where the container is to have a square or rectangular cross-section, although the container may, of course, be made of other polygonal cross-sectional shapes, such as triangular or polygonal. Securing flaps are provided at each end of the series of wall panels, which are designed to be folded over and directed inwardly from one of the corners of the package when set up, such flaps bearing adhesive on non-corrugated surfaces thereof which are brought into contact with each other and adhered so as to provide within such corner of the package an inwardly-directed, relatively firm brace, the inner edge of which may be formed with a suitable arcuate or scalloped portion or portions with curvatures corresponding to those of the object to be packed and so as to embrace a portion of the arcuate surface for example in

2

the case of a lamp bulb. This brace means will be relatively firm or rigid, inasmuch as its outer surfaces each will include portions of the corrugated sheet and thus such brace means, in conjunction with two adjacent wall portions of the container, will engage the bulb or the like at three spaced regions, thus firmly holding the bulb in place while at the same time having a bracing effect on the container as a whole, checking any tendency which might otherwise occur for the container to become distorted or rounded at its corners. In case the containers are made and shipped in flat blank form to the place where they are to be used for packaging objects, then the non-corrugated surfaces of the securing flap portions thereof may be covered with a suitable cohesive coating, such for example as disclosed in U.S. patents to Jennings, Nos. 2,432,074 and 2,432,075, or to Copeman et al., No. 2,704,732, reference to which is hereby made. Then before or after the object to be packed is placed on or surrounded by the blank, the cohesive-coated flaps may be pressed together

10 to provide the brace means above referred to, for engaging the object within the package. In cases where the blank is folded to form a carton-like package before shipment to the user, then the closure flaps may be adhered together by any suitable conventional type of adhesive.

15 In some cases it may be desirable also to coat the inner corrugated surfaces of the package with a cohesive material such as above referred to and which will not have such tackiness as to tend to adhere to the contained objects, but which will nevertheless have a high coefficient of friction with respect thereto, thereby tending more securely to retain the object in place against slippage out of position.

20 Various further and more specific objects, features and advantages of the invention will appear from the description given below, taken in connection with the accompanying drawings, illustrating by way of example a preferred form of the invention.

In the drawings:

25 FIG. 1 is a perspective view of a package made in accordance with the invention;

30 FIG. 2 is a plan view of a preferred form of blank for forming a container in accordance with the invention;

35 FIG. 3 is a vertical sectional view of the container of FIG. 1 and illustrating its use for packaging a lamp bulb by way of example; and

40 FIG. 4 is a top view of the package of the form shown in FIG. 1.

45 Referring to the drawings in further detail, the container blank as shown in FIG. 2 may comprise a rectangular sheet of single-faced corrugated paperboard as at 10, formed with a plurality of creases or score lines as at 11, 12, 13, 14 and 15, for dividing the blank into four side wall panels as at 16, 17, 18 and 19 respectively, with securing flaps as at 20, 21 at each end of the series of panels. When the blank is folded to form a container, the corrugated surface is to be located on the interior while the reverse surfaces of said securing flaps are covered with a coating of cohesive or adhesive material, as above referred to, and as indicated at 20', 21'.

50 At appropriate locations along on the edges of the securing flaps, same are formed with cut-out portions as at 22, 23, which will generally be arcuate or scalloped or will otherwise be shaped so as to conform with and to engage the surface of a frangible bulb or other object 24, which is enclosed in the finished package, as best shown in FIG. 3.

55 The blank may be folded into a box-like container with the flaps 20, 21, protruding inwardly from one corner, and adhered together as shown in FIGS. 1 and 4, and then the bulb 24, or other object to be packed, may be

slid into place to the positions best shown in FIGS. 3 and 4. Or if preferred, the blank, as of FIG. 2, may be in effect wrapped about the lamp bulb or the like, and thereafter the closure flaps which are coated with cohesive material, may be squeezed together to the condition best shown in FIG. 4, to complete the package.

It will thus be apparent that a very inexpensive container is provided which may be readily formed of a simple single-faced corrugated paperboard blank, while providing an effective internal retaining and brace means with little or no further expense for paperboard than is required for similar or conventional containers not having such brace means. That is, for conventional forms of corrugated paperboard containers, securing flap portions for the joint in the walls of the container must be provided in any event, and it will be apparent that the brace means in accordance with the present invention requires no extra paperboard material nor any manufacturing steps which would be more expensive than for similar boxes with wall joints conventionally formed. Also the invention provides a construction such that the blanks therefor may be readily shipped to the user in compact quantities while still spread out in flat condition and yet each blank can be thereafter folded around the object to be packed and the securing flaps cohered without the use of expensive equipment. Alternatively, the securing flaps may be initially adhered together and the cartons with only the corner 13 folded over flat, may be shipped in collapsed condition to the user.

While the container is preferably formed of single-faced corrugated paperboard, it will be understood that a single-faced laminate formed of flexible sheet material other than paperboard may be used such for example as various forms of plastic sheet material which generally should be of such a flexible nature that the brace means within the enclosure as above referred to will more or less yieldably retain the bulbous object against longitudinal displacement by reason of the object being embraced between the brace means and the opposite wall panels of the enclosure.

Although a certain particular embodiment of the invention is herein disclosed for purposes of explanation, possible modifications thereof, after study of this specification, will be apparent to those skilled in the art to which the invention pertains. Reference should accordingly be had to the appended claims in determining the scope of the invention.

What is claimed and desired to be secured by Letters Patent is:

1. A blank for forming a container for enclosing a bulbous object and comprising an elongated area of single-faced corrugated laminate of flexible sheet material, a plurality of spaced-apart transverse score lines being formed on said area for demarking the borders of wall panels when the blank is folded along said lines to form an enclosure of polygonal cross-section, relatively narrow

flap portions extending along each of the ends of said area, said flap portions on the surface reverse to the corrugated surface being coated with adhesive, said flap portions being adapted to be folded inwardly of the enclosure and adhered together to form brace means for protruding diagonally inwardly of a corner of the enclosure, the terminal edges of said flap portions being formed with curved cut-out areas adapted to be positioned to engage along a portion of the surface of the bulbous object to be contained in the enclosure for yieldably retaining the same against displacement.

2. A wrapper for containing a frangible bulb or the like object, comprising an enclosure of polygonal cross-section and formed of the container blank as specified in the foregoing claim 1, said blank being folded along said transverse score lines to form the enclosure of polygonal cross-section and said flap portions being folded inwardly of the enclosure and adhered together to form said brace means.

3: A package containing a frangible bulb or the like object, comprising an enclosure of polygonal cross-section and formed of the container blank as specified in claim 4, said blank being folded along said transverse score lines to form the enclosure of polygonal cross-section and said flap portions being folded inwardly of the enclosure and adhered together to form said brace means, the bulbous portion of the frangible bulb engaging the said curved cut-out areas and the opposite walls of the enclosure embracing and yieldably retaining the bulbous portion against displacement.

4. A blank for forming a container for enclosing a bulbous object and comprising an elongated area of flexible paperboard sheet material, a plurality of spaced-apart transverse score lines being formed on said area for demarking the borders of wall panels when the blank is folded along said lines to form an enclosure of polygonal cross-section, relatively narrow flap portions extending along each of the ends of said area, said flap portions on smooth surfaces thereof being coated with adhesive, said flap portions being adapted to be folded inwardly of the enclosure and adhered together to form brace means for protruding diagonally inwardly of a corner of the enclosure, the terminal edges of said flap means portions being formed with curved cut-out areas adapted to be positioned to engage along a portion of the surface of the bulbous object to be contained in the enclosure for yieldably retaining the same against displacement.
